SELF-CONTAINED FIRE ALARM UNIT

Edward Ehlers, Jr., Montclair, N. J.

Application May 5, 1955, Serial No. 506,296

2 Claims. (Cl. 340—227)

This invention relates to a self-contained fire alarm unit adapted to be mounted on a wall, ceiling or other surface of a room or other space to be served thereby.

The invention has for an object to provide a fire alarm unit comprising an electrically actuated alarm device, a dry battery as a source of electrical energy in circuit with said alarm device, said circuit including a thermostatic switch adapted to close in response to abnormal rise in temperature, such as produced by fire, and a push button actuatable test switch in shunt circuit between the battery and alarm device, these elements being all compactly contained in a single housing or casing, and said casing being so constructed as to transmit both air borne radiant heat and conducted heat to the thermostatic control switch.

The invention has for a further object to provide a casing including a rearwardly open hollow base plate upon which the elements of the fire alarm unit are mounted, with the thermostatic alarm control switch arranged in such relation thereto and direct contact therewith that heat conducted by and through the base plate will be rapidly transmitted to said switch in addition to radiant or air borne heat which enters the casing, whereby said switch is rendered more quickly responsive to abnormal rise of temperature, and to this end to provide a base plate comprising in whole or in part a highly heat conductive metal, such as copper.

The above and other objects will be understood from a reading of the following detailed description of the invention in connection with the accompanying drawings, in which:

Fig. 1 is a front elevational view of the self-contained fire alarm unit of this invention; Fig. 2 is a front elevational view of the same, with the cover member of the casing removed; Fig. 3 is a longitudinal sectional view, with parts in elevation, this view being drawn on an enlarged scale; and Fig. 4 is a cross-sectional view, taken on line 4—4 in Fig. 2, but drawn on an enlarged scale.

Referring to the drawings, in which like characters of reference indicate corresponding parts, the reference character 10 indicates the rearwardly open hollow base plate of the fire alarm unit housing. Mounted on the external face of the base plate 10, adjacent to the upper end thereof, is an electrically actuated alarm device 11, having at its back a supporting bracket 12 which is affixed to the base plate 10 by a fastening screw 13. This alarm device may be of any well known sound producing type, but preferably comprises an electric horn.

Mounted on the base plate 10, below the alarm device 11 is a dry battery 14, which serves as the source of electrical energy by which the alarm device is actuated. Said battery is secured in place by retaining clips or lugs 15 which are struck out from the material of the base plate, so as to embrace the sides, top and bottom of the battery.

Also mounted on the base plate 10, at its upper end, is a thermostatic switch 16. In a preferred form there-

2

of, this thermostatic switch comprises a hollow metallic casing formed by a bottom member 17 and a top member 18, and containing a bimetallic switch arm 19, which is electrically insulated from said casing by insulation 20, and a stationary contact 21, which opposes the switch arm 19 and is electrically grounded on the casing, said casing, in turn, being electrically grounded on the base plate 10 (see Fig. 4).

One pole 22 of the battery 14 is connected to one pole of the alarm device 11 by a lead 23, and the other pole of said alarm device is electrically grounded on the base plate 10. The alarm actuating circuit is completed through the base plate ground to the grounded stationary contact 21 of the thermostatic switch, and thence, when closed by engagement of the bimetallic switch arm 19 with said stationary contact 21, through said switch arm and a lead 24 connected therewith back to the other pole 26 of the battery 14.

To enclose the above described elements of the fire alarm unit, a hollow casing or cover member 27 is suitably attached to the base plate 10. This casing or cover member 27 is provided in its face wall, and opposite the alarm device 11, with louvered openings 28, through which the sound of the actuated alarm device can be unimpededly emitted. The bottom end wall of the casing or cover member 27 is provided with admission openings 29 through which radiant heat or air borne heat can pass upwardly into the interior of the fire alarm unit.

Suitably mounted in and through the front wall of the casing or cover member 27, preferably adjacent to the bottom end thereof, is a push-button actuatable test switch 30. One pole 31 of this test switch is connected by a lead 32 to the electrical ground provided by the base plate 10, and the other pole 33 of said test switch is connected by a lead 34 to the pole 26 of the battery 14. By this arrangement the test switch 30 is connected in a shunt circuit from the battery 14 through the alarm device 11 and back to said battery. When the push-button actuatable switch 30 is manually closed, current flows from the battery 14 through the alarm device 11 to ground, and thence back to the battery through the lead 34; thus providing a test circuit independent of the thermostatic switch 16, by which operable condition of the alarm device can from time to time be ascertained.

Provided in the upper end portion of the base plate 10 is a key hole type opening 35, whereby to engage the fire alarm unit with a mounting screw (not shown) which serves to support the fire alarm unit on and in contiguous contact with a wall or other surface within the room or other space desired to be served by said unit. When so mounted, the interior of the hollow base plate is opposed to the supporting surface, whereby heat emanating from said surface is confined in the hollow interior of the base plate, and thus concentrated therein for direct application to the base plate so as to be conducted thereby directly to the thermostatic switch (see Fig. 3).

From the above it will now be apparent that the present invention provides a very compact self-contained fire alarm unit, which is well adapted for room or like service.

One of the deficiencies of thermostatically controlled electric fire alarm devices, as heretofore known, is that the same depend, for operation, practically solely upon application thereto of radiant or air borne heat generated within the building room or space served thereby. Since fires, and particularly fires starting in the lower regions of a building, frequently progress through the building wall interiors before actually entering rooms or spaces contiguous to said walls, and since, under such circumstances, generation of radiant or air borne heat within such rooms or spaces is likely to be delayed, said former

devices are not well adapted to detect and give prompt warning of the existence and progress of internal wall fires. Having this in view, the present invention seeks to provide a novel construction of fire alarm unit which overcomes such deficiency, by providing said unit with a highly heat conductive path through which heat, generated within a wall on which the unit is mounted, will be quickly and directly conducted and applied to the thermostatic switch element, even before the air temperature within the room rises to an alarm actuating degree. To this end, the fire alarm unit of this invention is provided with the rearwardly open hollow base plate 10, which is effective to concentrate wall emitted heat directly against the base plate, includes a metal of high heat conductive characteristic, such as copper or other highly heat conductive metal.

Although the base plate 10 may be provided solely from copper or like highly heat conductive metal, since however such metals are relatively soft, and therefore easily deformed it is preferred to provide the base plate 10 with a core 36 of relatively rigid metal, such as steel, and then plate the surfaces thereof with an external coating 37 of copper or other highly heat conductive metal, which coating provides the base plate with the desired highly conductive heat path.

The casing 17-18 of the thermostatic switch 16 is mounted in direct contact with the heat conductive copper or like coating 37 of the base plate 19, and is held in place by retaining clips or lugs 25 which are struck up out of the base plate, so that the heat conductive copper or like coated portions of said clips or lugs contact the opposite sides of the switch casing 17-18, with enhanced conducted heat transfer effect. Heat emanating from a wall upon which the fire alarm unit is mounted will be confined in the base plate chamber and, will be quickly transferred directly to the base plate 19, and thereupon will be rapidly conducted to the thermostatic switch 16 by way of the highly heat conductive path provided by the copper or like coating 37 of said base plate.

Radiant or air borne heat can enter the interior of the casing or cover member 27 through its bottom openings 29, so as to rise therein for contact with the thermostatic switch 16. Such entering radiant or air borne heat also contacts and is transferred to the copper or like coating 37 of the base plate 19, so as to be rapidly conducted thereby to the thermostatic switch in addition to the direct contact of the radiant or air borne heat with the latter, thereby assuring operation of said switch in response to heat within a minimum interval of time.

Having now described my invention, I claim:

1. A self-contained fire alarm unit comprising a rearwardly open hollow base plate providing a chamber to confine heat emanating from a surface contiguous to which the unit is mounted, whereby to concentrate said heat in direct contact with the base plate for conduction thereby, an electrically actuated alarm device mounted on said base plate, a dry battery mounted on said base plate, a thermostatic switch, a heat conductive support for said thermostatic switch also mounted on said base plate, and a circuit connecting said alarm device and thermostatic switch in series with said battery, an enclosing hollow cover supported by said base plate, said cover having openings therein to admit radiant and air borne heat for contact with said thermostatic switch, and said base plate including a coating of highly heat conductive metal, such as copper, said support of the thermostatic switch being disposed in direct contact with said heat conductive metal coating of the base plate for reception of conducted heat therefrom.

2. A self-contained fire alarm unit comprising a rearwardly open hollow base-plate having a rigid metallic core plated with an external coating of a highly heat conductive metal, such as copper, said base plate providing a chamber to confine heat emanating from a surface contiguous to which the unit is mounted, whereby to concentrate said heat in direct contact with the base plate for conduction thereby an electrically actuated alarm device mounted on said base plate, a dry battery mounted on said base plate, a thermostatic switch, a heat conductive casing enclosing said thermostatic switch, said casing being mounted on said base plate in direct contact with the heat conductive coating thereof for reception of conducted heat therefrom, a circuit connecting said alarm device and thermostatic switch in series with said battery, and a hollow cover supported by said base plate, said cover having openings therein to admit radiant heat and air borne heat for contact with the thermostatic switch.
